UNITED STATES PATENT OFFICE.

HENRY PRICE BALL, OF NEW YORK, N. Y., ASSIGNOR OF ONE-HALF TO
SAMUEL INSULL, OF CHICAGO, ILLINOIS.

PERFORATING DEVICE FOR MUSIC-ROLLS.

SPECIFICATION forming part of Letters Patent No. 766,803, dated August 9, 1904.

Application filed April 18, 1902. Serial No. 103,482. (No model.)

To all whom it may concern:

Be it known that I, HENRY PRICE BALL, a citizen of the United States, residing at New York city, county and State of New York, 5 have invented a Perforating Device for Music-Rolls, of which the following is a specification.

My invention relates to a perforating device for music-rolls; and it consists in a construction whereby the space occupied by the punch 10 will correspond to the width of the strip or strips of paper to be perforated and be much less in length than that of the combined mechanism for operating the punches, the object of 15 my invention being to produce a machine wherein the devices for actuating the punches are given an abundance of room within which to perform their necessary functions, while the punches themselves are confined to a space the width of the paper to be perforated.

20 The accompanying drawings will serve to illustrate my invention.

Figure 1 is a top view. Fig. 2 is a section taken on the line X X of Fig. 1. Fig. 3 is a side elevation showing the device for holding 25 the moving paper when the punch is passing through it. Fig. 4 is a vertical section showing a number of strips of paper to be perforated for a music-roll to be wound upon a roller.

30 In the drawings, 5 indicates the sides of the main supporting-frame, and 6 the sides of an extension from this frame, which frame is slightly wider than the paper to be perforated and narrower than the main frame. Journaled in the main frame is a shaft 7, on which 35 is mounted a series of cams 8. Between the cams and secured to the shaft 7 are the toothed wheels 9. Pivoted to the cams 8 are the latches 10.

40 11 and 12 are pivoted bell-cranks in the path of movement of the latches 10 on the cams 8. 13 represents cords which are assumed to be connected to the keys of a piano or other suitable device and which when depressed 45 will serve to actuate the bell-cranks 11 and 12. Such keys, cords, and their co-operating parts may be termed "permissive" devices for controlling the action of the individual punches of the punching mechanism.

14 indicates a pivoted latch, which may be 50 employed in connection with a bell-crank 12, as indicated by the dotted lines, to throw such bell-crank out of action—*i. e.*, out of the path of movement of the cam 8—when desired, as will be hereinafter described. 55

Mounted on the end of the shaft 7 is a gear 15, which meshes with a small gear 16 on shaft 17, which has its bearing at one end in the side of the frame 5 and in the sides of the frame 6. On the opposite end of the shaft 17 60 is a beveled gear 18, in mesh with a beveled gear 19 on shaft 20. The shaft 20 is provided with a worm 21, which takes in a worm-wheel (not shown) mounted underneath it on shaft 32.

65 Mounted on each end of the shaft 17 is an eccentric 23, carrying a die-seat 24, having the central openings 25 and adapted to reciprocate within the fixed guide 26, which is secured to the side frame 6.

70 Arranged transversely of the main frame 5 is a rod 27, and loosely mounted on this rod is a series of levers 28, each provided with a downwardly-projecting arm 29, located in the path of movement of the periphery of a cam 8. Connected to each lever 28 through 75 a link 30 is an angularly-disposed lever 31, loosely pivoted in the bar 32, which is secured to the top of the frame 5. Connected to the opposite end of each lever 31 is a punch 33, which reciprocates through the guide 26 and 80 central openings 25 of the die-seat 24.

85 34 is a spring which normally tends to draw the lever 31 upward at its forward end.

M indicates a strip or strips of paper or other material to be perforated. These strips are wound upon the roller 35 and when in motion pass in the direction of the arrow over the rollers 36 37 and onto the take-up roller 38. Motion is given to such strips of paper or other material by means of the shaft 22, 90 which bears upon the periphery of the paper upon the rolls 35 38. The movement of the strip M over the die-seat 24 is a step-by-step movement, owing to the fact that the paper is held from moving continuously forward under the punches when the punches are perforating the paper. This step-by-step movement of the paper, however, forms no part of 95

the invention. Owing to the step-by-step movement, it is necessary to hold the strip of paper in a fixed position on the die-seat when the punches are passing through it, and to prevent its tearing. To accomplish this result, the machine may be provided with the devices for holding the paper shown in Fig. 3. In this figure there is shown as located within the cavity of the guide 26 a plunger 39, over which is arranged a spring 40. When the die-seat 24 is raised through the action of the eccentric 23, the paper is held between such parts and prevented from moving.

I have described as located under one or more of the bell-cranks 12 the latches 14. The object of this arrangement is to provide for throwing such of the punches—*i. e.*, the two outside punches which are usually employed for punching the rack-holes in the moving paper or strip—out of operation when it is desired that no rack-holes shall be punched.

One of the cams which usually operate the rack-hole punches is indicated at 41, Fig. 2. This cam differs slightly in shape from the cams 8 in order that the rack-hole punches shall make a continuous up-and-down movement, punching successive holes through the paper irrespective of the action of the punches which pass through the paper to indicate the musical notes.

I wish it understood that I do not limit myself to the precise features of construction shown in the accompanying specification and drawings for punching a music-roll of less width than the punching device, as very many changes may be made without departing from the intent of my invention.

Certain features of the mechanism described in this case have heretofore been disclosed and claimed in my application, Serial No. 97,353, filed March 8, 1902, and to such I now make no claim.

Having thus described my invention, I claim—

45 1. A perforating-machine for music-rolls, embodying in its construction a driven shaft, a series of cams loose on said shaft, means for throwing the cams into engagement with the driven shaft, a series of punches, and a series 50 of levers between the punches and the cams and actuated by said cams.

2. A perforating device for music-rolls, embodying in its construction a series of cams, means for causing said cams to be individually rotated, a series of punches, and a series 55 of levers between said punches and said cams.

3. A perforating device for music-rolls, embodying in its construction a series of separate cams, means for actuating one or more 60 of said cams, a series of pivoted levers operated by said cams, and a series of punches moved by said levers.

4. A perforating device for music-rolls, embodying in its construction a driven shaft, a 65 series of cams on said shaft, means for throw-

ing said cams into engagement with said shaft, a series of levers coacting with said cams, a series of punches actuated by said levers, a second driven shaft, an eccentric continuously reciprocated by said shaft, and a die-seat actuated by said eccentric. 70

5. In a perforating device, such as described, a series of punches, a continuously-reciprocating die-seat, common to all the punches, and means for reciprocating any of the 75 punches into engagement with the die-seat at the will of the operator.

6. In a perforating device, such as described, a series of punches, a continuously-reciprocating die-seat common to all the punches, 80 means for reciprocating the die-seat, means for reciprocating any of the punches into engagement with the die-seat, said means being timed in its movements to the movements of the die-seat, and means for causing the material to be perforated to be fed between the punches and die-seat. 85

7. In a perforating device such as described, a series of punches, a continuously-reciprocating die-seat common to all the punches, and 90 means for reciprocating one or more of the punches into engagement with the die-seat at the will of the operator, said means arranged to throw the punches into engagement with the die-seat for a period of time, less than the 95 time employed by the operator in holding the device in its operating position.

8. In a perforating device such as described, a driven shaft, having a series of cam members thereon capable of being thrown into and out of engagement with the shaft, at the will of the operator, a second shaft having a series of punching members thereon said shaft less in longitudinal length than the driven shaft, and intervening mechanism, whereby motion 100 is transmitted from the cam members on one shaft to the punching members on the other shaft. 105

9. In a perforating device such as described, a driven shaft having a series of members 110 thereon capable of being engaged or disengaged from the shaft at the will of the operator, a second driven shaft timed in its speed to the first-named shaft, a series of punching mechanisms on the second shaft occupying in 115 length on the shaft a space approximately equal to the width of a music-roll sheet, and intervening means between the two sets of members on the shafts, whereby the first-named shaft and its members can be of any 120 length as compared with the second shaft.

10. In a perforating device, such as described, a series of punches, a continuously-reciprocating die-seat common to all the punches, means for throwing one or more of 125 the punches into engagement with the die-seat at the will of the operator, and means for shortening the duration of the time of such engagement by a certain predetermined amount. 130

11. In a perforating device such as described, a series of punches, a continuously-reciprocating die-seat common to all the punches, means for throwing one or more of the punches into engagement with the die-seat at the will of the operator, means for advancing the paper to be perforated over the die-seat, and means whereby the paper is advanced a certain predetermined amount between successive engagements of any individual punch as thrown in by the operator.

12. In a perforating device such as described, a series of punches, a continuously-reciprocating die-seat common to all the punches, means for throwing one or more of the punches into engagement with the die-seat at the will of the operator, and means whereby a certain amount of paper must be fed forward between the disengagement of any particular punch and its reengagement with the die-seat and independent of the operator.

13. A perforating-machine for music-rolls, embodying in its construction a driven shaft, a series of members normally disengaged from but mounted on said shaft, means for throwing one or more of the said members into or out of engagement with the shaft, a series of punches one for each member on the shaft, and means actuated by said members for throwing the punches into and out of engagement.

14. A perforating device for music-rolls, embodying in its construction a series of cams, means for causing said cams to be individually rotated, a series of punches, and means for transmitting the motion of the cams to the punches.

15. A perforating device for music-rolls, embodying in its construction a series of cams, a common driver for the same, and means for causing one or more of said cams to be individually actuated thereby, a series of punches one for each cam thrown into and out of action by the movement of the cam.

16. In a perforating device for music-rolls, a series of independent cams thrown into or out of action at the will of the operator, and a series of punches corresponding in number to the number of cams; the punches being thrown into and out of action by the movement of their respective cams.

17. A perforating device for music-rolls, embodying in its construction a series of separate cams, means for energizing one or more of the cams, and a series of punches actuated by the cams.

18. A perforating device for music-rolls,

embodying in its construction a series of punching mechanisms, occupying in width a space practically equal to the width of the music-sheet, a second series of mechanically-driven mechanisms of greater width, actuated at the will of the operator, and means for transmitting motion from one set of mechanisms to the other.

19. In a perforating device for music-rolls, embodying in its construction two sets of co-acting mechanically - driven mechanisms of different widths, one set being thrown out of engagement at will, the other set of mechanisms acting to perforate the paper passing through the machine.

20. In a machine such as described, a series of punching mechanisms, means continuously tending to throw the mechanisms into action, and a series of restraining means preventing the punching mechanisms from acting excepting at the will of the operator.

21. In a perforating device such as described, a series of punching mechanisms normally inactive but tending to throw themselves into action, and a series of restraining means thrown out of engagement therewith by the operator.

22. In a machine such as described, a series of punches, and a strip of paper passing through the machine to be perforated, means continuously acting to throw the punches into perforating engagement with the paper, independent restraining means for each punch, and means whereby one or more punches can be released therefrom.

23. A perforating device for music - rolls embodying in its construction, a driven shaft, a series of toothed wheels secured to said shaft, a series of cams loose on said shaft, means under the control of the operator for throwing the individual cams into and out of engagement with the shaft, a series of punches, and means for moving the punches introduced between the punches and the cams.

24. A perforating device for music - rolls embodying in its construction, a series of permissive devices under the control of the operator, a series of punches carried by levers, and mechanism introduced between said permissive devices and punches for throwing said punches into operation a definite time after the action of the permissive devices.

In testimony whereof I affix my signature in the presence of two witnesses.

HENRY PRICE BALL.
